UNITED STATES PATENT OFFICE.

VINCZENZ ZSUZSITS, OF AURORA, ILLINOIS.

ANTIREFILLABLE BOTTLE.

1,072,895.

Specification of Letters Patent.

Patented Sept. 9, 1913.

Application filed November 11, 1912. Serial No. 730,677.

To all whom it may concern:

Be it known that I, VINCZENZ ZSUZSITS, a subject of the King of Hungary, residing at Aurora, in the county of Kane and 5 State of Illinois, have invented certain new and useful Improvements in Antirefillable Bottles, of which the following is a specification, reference being had therein to the accompanying drawing.

10 This invention relates to an antirefillable bottle, and the primary object of my invention is to provide a bottle or other receptacle with a novel by-path that is arranged and equipped with a check valve whereby 15 the contents of the bottle can be removed through the by-path, but the refilling of the bottle impossible unless the same is disfigured.

20 A further object of this invention is to provide an anti-refillable bottle that can be advantageously used for dispensing poisons and liquids that are detrimental to the health, it being practically impossible for the bottle to be refilled and used for other 25 purposes.

With the above and other objects in view the invention resides in the novel construction, combination and arrangement of parts 30 to be hereinafter specifically described and then claimed.

Reference will now be had to the drawing, wherein:—

Figure 1 is a vertical sectional view of a bottle in accordance with this invention, Fig. 35 2 is a horizontal sectional view of the same, Fig. 3 is a front elevation of the bottle, Fig. 4 is a horizontal sectional view illustrating a check valve, Fig. 5 is a side elevation of one of the closures of the bottle, and Fig. 6 is a similar view of another closure of the bottle.

40 45 50 55 1 denotes a bottle having a breast 2 provided with a neck 3 and the lower end of the neck has a seat 4 and an annular interior groove 5.

Mounted in the bottle neck 3 is a closure 6 that has the lower end thereof provided with a gasket 7 adapted to engage the seat 4 and seal the bottle neck. The closure, adjacent to the upper end thereof has an annular groove for a packing ring 8 and between said packing ring and the gasket 7 is a pocket 9 for a locking pin 10 that extends into the groove 5 and is retained therein by a coiled compression spring 11 arranged within the pocket 9. The closure 6 is easily

removed from the mouth of the bottle neck and after having once been placed in the neck of a bottle it is impossible to remove the same without injuring the bottle.

Formed integral with the breast 2 and the neck 3 is an enlargement in the form of an auxiliary neck 12. The neck 12 has communicating recesses 13 and 14 with the recess 13 in communication with the bottle 60 through the medium of a tapering port 15. The recess 14 is in communication with a closure seat 16 and a curved by-path 17, said by-path establishing communication between the main and the auxiliary necks. 65

The port 15 receives a check valve 18 in the form of a spherical body and arranged in the recess 13 and engaging the valve 18 are a plurality of balls 19 that are engaged by a large hollow ball 20 arranged within the recess 14. The ball 20 is retained within the recess 14 by a closure 21 screwed into the auxiliary neck, said closure having a flange 22 engaging a gasket 23 arranged upon the seat 16. The flange 22 has a spring pressed locking pin 24, similar to the locking pin 10, that engages in a socket 25 provided therefor in the auxiliary neck. 70 75 80

There is sufficient play between the closure 21 and the balls 20 and 19 to permit of the valve 18 being unseated when it is desired to pour liquid from the bottle 1, otherwise the check valve 18 remains in a lowered and closed position, and the main bottle neck permits of an ordinary stopper 90 being used to coöperate with the check valve in preventing the contents of a bottle from evaporating.

After the closures 6 and 21 have been placed in position it is impossible to refill the bottle, consequently there is little danger of it being used for purposes other than for which it is intended.

One embodiment of my invention has been illustrated, but it is to be understood that the structural elements are susceptible to such modifications and variations as fall within the scope of the appended claim.

What I claim is:—

In an anti-refillable bottle, a main bottle 105 neck, a closure arranged in the lower portion thereof and locked thereto, an auxiliary bottle neck formed integral with the breast of the bottle and with one side of the bottle neck, said auxiliary bottle neck 110 formed with communicating recesses and further having a tapering port for estab-

lishing communication between one of said recesses and the interior of the bottle, said bottle necks formed with a curved port for establishing communication between the other of said recesses and the interior of the main bottle neck, a spherical valve normally closing said port, shiftable spherical bodies arranged in said recesses and engaging said valve for normally maintaining it seated, and a closure arranged within the outer end of the auxiliary neck and locked

thereto for confining the movement of said spherical bodies, said auxiliary bottle neck being of greater diameter than said main bottle neck and said spherical bodies of greater diameter than said valve.

In testimony whereof I affix my signature in the presence of two witnesses.

VINCZENZ ZSUZZSITS.
